UNITED STATES PATENT OFFICE

ALBERT D. KETCHUM, SR., OF CHICAGO, ILLINOIS

RAILROAD CROSSING

Application filed July 2, 1929. Serial No. 375,542.

This invention relates to certain novel improvements in railroad crossings and has for its principal object the provision of an improved arrangement of this character which will be simple in use and economical to manufacture.

The salient object of my invention is to provide a railroad crossing for intersection trackways which will be arranged in a manner such that the usual frog arrangements may be dispensed with.

An object of the invention, ancillary to the foregoing, is to provide a crossing arrangement for intersecting trackways which will be arranged in a manner such that the noise usually attendant to the crossing of one trackway by a train on another trackway will be substantially eliminated.

A further object of the invention is to provide an arrangement of the above described character which will be constructed in a manner such that the intersecting trackways will be disposed in different horizontal planes.

A still further object of the invention is to provide an arrangement whereby one of the trackways may be moved to and from position relative to the other of the trackways dependent upon which of the trackways is to carry the succeeding train.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is a plan elevational view of a preferred form of construction for my invention;

Fig. 2 is a sectional view taken substantially on the line 2—2 on Fig. 1;

Fig. 3 is a sectional view taken substantially on the line 3—3 on Fig. 2; and

Fig. 4 is a sectional view taken substantially on the line 4—4 on Fig. 3.

In the accompanying drawing wherein a preferred form of construction for my invention is illustrated, 10 indicates a trackway

comprising parallel rails 11 and 12 mounted on the usual ties 13 that are imbedded in a road bed formed in the approved manner.

Another trackway 14 is depicted in the accompanying drawing which is intended to cross the trackway 10 and this trackway includes parallel rail sections 15 and 16 that are disposed on one side of the trackway 10. Aligned with the rails 15 and 16 are rails 17 and 18 which also form a portion of the trackway 14 but which are disposed on the opposite side of the trackway 10. The rails 15 and 16, and 17 and 18 are mounted on ties 19 which are mounted in a road bed of approved construction. The road bed supporting the trackway 10 is intended to be disposed at a lower horizontal level than the road bed supporting the trackway 14.

My improved invention resides in the construction employed for interconnecting the track sections 15 and 17, and 16 and 18 and this arrangement extends across the trackway 10 and includes the following mechanism. Rail sections 20 and 21 are provided which respectively extend between the rail sections 15 and 17, and 16 and 18. As is best illustrated in Figs 1 and 2 the rail section 20 has a substantially L-shaped formation 22 provided thereon at the end thereof disposed adjacent the rail 15 and the stem portion of this L-shaped formation is preferably disposed outwardly with respect to the trackway 14. A projection 23 is provided on the rail section 15 which extends along the stem portion 22 interiorly thereof to the base portion of said L-shaped formation. The juncture of the portion 23 with the rail section 20 and the juncture of the projection 22 with the rail section 15 are tapered in a vertical plane as clearly illustrated in Figs. 1 and 2 and the rail section 20 is arranged in a manner set forth hereinafter for movement upwardly away from the rail section 17 and these tapered portions which are indicated by 24 are inclined at an angle which will permit this movement, it being understood that the portions which were just set forth are arranged for movement in a vertical plane inasmuch as the support for the rail section 20 is arranged intermediate the ends thereof.

The juncture between the rail section 20 and the rail section 17 is arranged in a manner similar to that set forth. Similarly the rail sections 16 and 21, and 18 and 21 are joined in a like manner.

5 The rail sections 20 and 21 are mounted on a plate 25 which embodies sufficient rigidity to properly support these rail sections. Extending through the co-extensive projecting 10 portions of the rail sections 20 and 15, and 21 and 16 is a shaft 26 which is fixed to the projections on the rail sections 20 and 21 but which is rotatable in the projections on the rail sections 15 and 16.

15 A pit 27 is formed below the end of the rail sections 15 and 16. In this pit 27 suitable motive means such as an electric motor 28 is arranged. In this connection I may provide wires leading from the motor 28 to 20 block systems associated with the trackways 13 and 14 so that when a train is approaching on the trackway 13, the motor 28 will be energized from a suitable source of electric power and the rail sections 20 and 21 lifted 25 into vertical position. I may accordingly arrange the circuit in such a manner that after the train has passed the intersection and has passed out of the block on the trackway 13, the motor 28 will be deenergized and in 30 this manner the track sections 20 and 21 lowered into horizontal position. A shaft 29 is supported in bearings 30 and 31 carried by the upper plate 32 covering the pit 27. A gear 33 is fixed on the shaft 29 and meshes 35 with a gear 34 on the shaft of the motor 28. Fixed on the shaft 26 is a sprocket 35 and fixed on the shaft 29 in alignment with the sprocket 35 is a sprocket 36 and a chain 37 extends between these sprockets. A sprocket 38 is fixed on the shaft 26 and a sprocket 39 40 is fixed on the shaft 29 and a chain 40 extends between these sprockets. When the motor 28 is set in operation, movement thereof is transmitted through the gear 34 to the gear 33 to the shaft 29 thence through the sprockets 36 and 39 to the chains 37 and 40 to the sprockets 35 and 38 to the shaft 26. When the motor 28 is rotated in the proper direction the shaft 26 is rotated so as to move the 45 plate 25 and the rail sections 20 and 21 upwardly and this movement is carried out until these rail sections extend substantially perpendicular.

It is manifest that the rail sections 20 and 50 21 and the plate 25 extend for an appreciable distance from the pivotal mountings thereof and it is, therefore, very advantageous that the weight thereof be counterbalanced and this is accomplished in the following manner. 55 Extending across the pit 27 is a shaft 41 which is journaled in bearings 42 and 43. Fixed on the shaft 26 is a gear 44 which meshes with a gear 45 fixed on the shaft 41. A gear 46 is fixed on the shaft 26 and meshes with a gear 60 47 fixed on the shaft 41. Therefore, when

the shaft 26 is rotated in the manner here-
into set forth movement thereof will be
transmitted through the gears 44 and 46 to
the gears 45 and 47 and thence to the shaft 41.
Fixed on the shaft 41 is a weight 48 which em-
bodies a mass sufficient to effectively counter-
balance the overhanging of the rail sections
20 and 21 and the plate 25. Due to this coun-
ter balance arrangement very little power
will be required to operate the shaft 26 to
elevate the rail sections 20 and 21 in the man-
ner set forth.

70 It is apparent that when the rail sections
20 and 21 are arranged in the perpendicular
position described unimpeded passage may
be had over the trackway 13. However, when
the device is operated so as to position the
rail sections 20 and 21 in the position illus-
trated it is apparent that passage over the
track way 13 is closed but that passage from
the rail sections 15 and 16 to the rail sections
17 and 18 over the track sections 20 and 21
is possible. It is, therefore, apparent that the
intersection of crossing railways may be ar-
ranged in a manner such that the usual frog
structures may be eliminated.

75 A reenforcing plate such as that indicated
at 49 may be provided at the juncture between
the rail sections 20 and 21 with the rail sec-
tions 17 and 18 which is obviously the sepa-
rating parts of these rail sections.

80 In order to insure proper guiding of a train
onto the device the guiding mechanism gener-
ically indicated by 50 is associated with the
track sections 15 and 16 which track sections
are disposed on the side of the device from
which the train is to approach. This guiding
structure includes a substantially V-shaped
formation 51 which has the apex thereof
extended in the direction from which the
train is approaching and associated with the
outer end of one of the arms of the V-shaped
structure 51 is a guide plate 52 which directs
the flanges on the tires of the wheels of the
train into proper engagement with the inner
sides of the rail sections 20 and 21.

85 A block system of approved form is pref-
erably associated with the device and this
block system is arranged so that when the
rail sections 20 and 21 are in the position illus-
trated in the drawing the signals will
be set against trains approaching on the track
way 13. However, when the rail sections 20
and 21 are in the vertical position alluded to
these block signals will be set against trains
approaching on the trackway 14.

90 While I have illustrated and described the
preferred form of construction for carrying
my invention into effect, this is capable of
variation and modification, without depart-
ing from the spirit of the invention. I, there-
fore, do not wish to be limited to the precise
details of construction set forth, but desire to
avail myself of such variations and modifica-
95

tions as come within the scope of the appended claims.

Having thus described my invention what I claim as new and desire to protect by Letters Patent is:

1. In a device of the character stated, a trackway comprising rail members, supporting means for said rail members, a second trackway disposed above and extended across said first-mentioned trackway, said last-mentioned trackway comprising movable rail sections having angularly formed end portions adapted to provide connection with corresponding angularly formed end portions in the stationary rails aligned with said movable rail sections, supporting means for said movable rail sections including a plate member attached to said rail sections at the under sides thereof and movable therewith, means providing connection between said plate member and said rail sections, a rotatable shaft disposed at one end of said rail sections and journaled in the end portions of corresponding stationary rails, means for fixing corresponding end portions of said movable rail sections to said shaft, a housing disposed below said shaft, a plate member disposed at the top of said housing, a rotatable shaft carried by said last-mentioned plate member, means providing connection between said last-mentioned plate and said last-mentioned shaft, means providing connection between said first-named shaft and said second-named shaft, means for moving said rail sections and attached plate in a vertical plane, said last-mentioned means including power actuated means disposed in said housing, and means providing connection between said power actuated means and said second-named shaft whereby when said second-named shaft is rotated said first-named shaft will be rotated and said rail sections moved in a vertical plane away from said first-named trackway.

2. In a device of the character stated, a trackway comprising rail members, supporting means for said rail members, a second trackway disposed above and extended across said first-mentioned trackway, said last-mentioned trackway comprising movable rail sections having angularly formed end portions adapted to provide connection with corresponding angularly formed end portions in the stationary rails aligned with said movable rail sections, supporting means for said movable rail sections including a plate member attached to said rail sections at the under sides thereof and movable therewith, means providing connection between said plate member and said rail sections, a rotatable shaft disposed at one end of said rail sections and journaled in the end portions of corresponding stationary rails, means for fixing corresponding end portions of said movable rail sections to said shaft, a housing disposed below said shaft, a plate member disposed at the top of said housing, a rotatable shaft carried by said last-mentioned plate member, means providing connection between said last-mentioned plate and said last-mentioned shaft, means providing connection between said first-named shaft and said second-named shaft whereby when said second-named shaft is rotated said first-named shaft will be rotated and said rail sections moved in a vertical plane away from said first-named trackway.

the top of said housing, a rotatable shaft carried by said last-mentioned plate member, means providing connection between said last-mentioned plate and said last-mentioned shaft, means providing connection between said first-named shaft and said second-named shaft, a third rotatable shaft, said last-mentioned shaft being journaled in said housing, means connected to said last-mentioned shaft for counterbalancing the weight of said rail sections and attached plate, means providing connection between said third-mentioned shaft and said first-mentioned shaft, means for moving said rail sections and attached plate in a vertical plane, said last-mentioned means including power actuated means, means providing connection between said power actuated means and said first-mentioned shaft, and means for guiding and positioning said movable rail sections with respect to adjoining stationary rail members. 80 75 70 85 85

In testimony whereof I affix my signature.
